Patented Nov. 10, 1914.

UNITED STATES PATENT OFFICE.

DON A. MCCOY, OF MILLER, SOUTH DAKOTA.

FIRE-ESCAPE.

1,116,829.

Specification of Letters Patent. Patented Nov. 10, 1914.

Application filed September 23, 1913. Serial No. 791,350.

To all whom it may concern:

Be it known that I, DON A. McCoy, citizen of the United States, residing at Miller, in the county of Hand and State of South Dakota, have invented certain new and useful Improvements in Fire-Escapes, of which the following is a specification.

This invention relates to an improvement in fire escapes.

10 The primary object of the invention is to provide a fire escape which will be supported at all times on the outside of the building and convenient to the windows, the arrangement being such that when not in use 15 the apparatus may be disposed at one side of the windows where it will not in any way obstruct the window.

20 A further object of the invention is to provide a structure in which the fire escape may be brought into operative position from any floor of the building.

25 In the drawings: Figure 1 is a view showing the device arranged on a building, the pole or bar being indicated in dotted lines as folded against the building. Fig. 2 a 30 sectional view of the mechanism for supporting the pole against movement after the same has been brought to its operative position. Fig. 3 a front elevation of said 35 mechanism.

Corresponding and like parts are referred to in the following description and indicated in all the views of the accompanying drawings by the same reference characters.

40 The invention consists essentially in a pole which is swingingly mounted in suitable supports on the outside wall of a building and adjacent the windows thereof, so that, while it may be normally disposed flat against the wall, it may be readily 45 reached by an occupant of the room and swung outwardly into spaced relation to the wall, thus permitting the occupants of the room to make their escape from the room by sliding down the pole.

50 In the drawings, 10 designates the pole which may be made of any suitable material. The pole at its upper end is provided with an arm 11 and at its lower end with an arm 12. A bracket 13 is secured to the building adjacent the ground line, the bracket receiving an extension 14 of the arm 12. This bracket forms a support for the pole which permits the pole to be freely 55 swung, being limited, of course, in its movement by contact with the wall of the build-

ing. A similar bracket 15 is arranged adjacent the roof of the building, receiving an extension 16 of the arm 11. It will be noted by this construction that the pole may 60 be swung on its pivotal supports to dispose the same adjacent the wall and that a person upon any floor of the building may conveniently reach out of the window and swing the pole on its pivot, whereby the descent 65 to the ground may be made.

A yoke 17 is secured to the wall adjacent the bracket 15, the terminals of the yoke being secured to the building in any suitable manner. The yoke is provided with a 70 central strut or brace 18 which is secured to the wall of the building below the bracket. The arm 11 of the pole rides over the upper edge 19 of the yoke. The extensions of the arms 11 and 12 are of such length that the 75 pole may participate in a slight vertical movement, thus the pole may be swung to the center of the yoke and the arm 11 seated in a notch 20 formed in the upper edge 19 of the yoke. A retaining plate is mounted 80 immediately above the yoke 17 and disposed to bear against the arm 11 to maintain it in contact with the yoke, whereby when the arm is seated within the depression, swinging of the same is prevented until the arm 85 is raised.

The plate 21 is provided with a flange 22 by means of which the plate is secured to the wall of the building, and while the plate has been illustrated as the means for supporting the pole against movement, other 90 resilient means may be used or the yoke may be provided with a central latch member to receive the arm 11. It will be noted that in practice the occupants of the building may 95 conveniently grasp the pole and swing the same until it is seated in the notch 20 of the yoke, whereby further movement of the pole is prevented. Particular attention is called to the fact that when in use there is no 100 danger of the pole being raised and thereby forced out of the notch 20, as there is a constant downward pull exerted on the pole. The pole may be readily returned to its position adjacent the wall of the building by 105 lifting on the lower arm 12 and overcoming the downward pressure exerted by the plate 21, whereby the bar may be raised out of the notch and rotated upon its pivotal supports.

110 The many advantages of a construction of this character will be clearly apparent as it will be noted that when the device is

not in use the same is positioned adjacent the wall of the building where it does not obstruct the windows, the structure being such as to present a neat appearance. It will also be seen that the device may be easily and economically manufactured and positioned upon buildings without marring the walls or in any way altering the building construction.

Having thus described the invention what is claimed as new is:

1. A fire escape for buildings including a pair of vertically spaced supporting members, a pole having laterally offset terminals journaled therein, one of said supports including a yoke member having a notch adapted to receive the offset portion of the pole, and yieldable means for holding the offset portion in the notch when the pole is swung outwardly, whereby it is spaced from the building.
2. A fire escape for buildings including a pair of vertically spaced supporting members, a pole having laterally offset terminals journaled therein, one of said supports including a yoke member having a notch adapted to receive the offset portion of the pole, and yieldable means for holding the offset portion in the notch when the pole is swung outwardly, whereby it is spaced from

the building, said pole being adapted to be swung inwardly toward the building when the offset portion has been disengaged from the notch, said yieldable means tending to hold the offset portion against return movement when it is disposed at intermediate points between the notch and the building.

3. A fire escape for buildings including a pair of supporting members, a pole having laterally offset extensions the terminals of which are journaled in the supports, one of said supports including a yoke member having a notch adapted to receive an extension of the pole, and a resilient plate normally bearing against the adjacent extension of the pole and acting to hold the extension in the notch of the yoke, whereby the pole may be held against swinging movement when spaced from the building, said plate also tending to hold the extension against return movement toward the notch of the yoke when the pole has been swung to lie at a point intermediate the notch of the yoke and the building.

In testimony whereof I affix my signature in presence of two witnesses.

DON A. McCOY. [L. s.]
